ATTACHING TAPE

John V. Moore, Pawtucket, R. I., assignor to
 Moore Fabric Company, Pawtucket, R. I., a
 corporation of Rhode Island

Application July 3, 1939, Serial No. 282,599

1 Claim. (Cl. 139—384)

This invention relates to the type of separable connectors commonly termed "zippers" and relates more particularly to an improved attaching tape for such connectors.

5 It is the general object of my invention to provide an attaching tape which is in part elastic and in part non-elastic and which comprises an improved weave by which manufacture of the tape is simplified and made commercially practical.

10 My invention further relates to arrangements and combinations of parts which will be herein-after described and more particularly pointed out in the appended claim.

15 A preferred form of the invention is shown in the drawing, in which:

Fig. 1 is a plan view of a portion of my improved tape and showing the weave construction;

Fig. 2 is a diagrammatic sectional view further illustrating successive picks in the weave construction; and

Fig. 3 is a plan view of a portion of the tape with one part of a "zipper" connection affixed thereto.

20 Referring to the drawing, my improved tape T comprises a longitudinally extending transversely elastic section 10 adapted to be stitched to the edge of a garment or other article to be closed, and a non-elastic longitudinally-extending section 11 to which one part 12 of a "zipper" connection or other separable fastener may be secured.

25 A preferred weave for my improved tape T is shown in Figs. 1 and 2, in which the section 10 comprises non-elastic warps 20 and an elastic weft thread 21, these elements being illustratively shown as interwoven in a simple two-up and two-down rib weave.

30 The non-elastic section 11 comprises non-elastic warps 30, a non-elastic weft thread 31, and 35 also commonly includes a heavy cord 32 interwoven to form a reinforced outer edge to which the "zipper" part 12 may be secured.

35 While my invention is not necessarily limited to the particular weaves shown, I have indicated 40 the portion of the section 11 adjacent the elastic section 10 as woven two-up and two-down in a twill weave. At the extreme outer edge, the non-elastic section is made tubular to embrace the cord 32. The tubular structure is indicated in 45 Fig. 1 and will be evident in Fig. 2 if the upper and lower picks are folded forward and rearward over the middle pick as would be the case in the actual fabric.

While the particular weaves may be varied, it is desirable that the number of picks per inch of the elastic weft thread 21 and the non-elastic weft thread 31 be correlated, so that each pair of adjacent picks of the elastic thread 21 5 may be interlocked with a corresponding pair of adjacent picks of the non-elastic weft thread 31 along the line of the abutting margins of the elastic and non-elastic sections. The warp thread 34 at the margin of the section 11 may be heavier 10 or stronger than the other warp threads 30, as it serves as a catch thread to establish the line between the sections.

15 Successive and corresponding picks in Figs. 1 and 2 are lettered A to F in the elastic section 10 and A' to F' in the non-elastic section 11 respectively.

20 When made substantially in the manner described, my improved fabric may be easily and rapidly woven and is thus economical to manufacture and commercially practical.

25 When such a tape is installed for use, the reinforced non-elastic section 11 provides a firm base for attachment of one part 12 of the separable connector, while the elastic section 10, when attached to a garment or other article, provides a slight transversely yielding action which much improved the operation of the "zipper".

30 Having thus described my invention and the advantages thereof, I do not wish to be limited to the details herein disclosed, otherwise than as set forth in the claim, but what I claim is:

35 A woven attaching tape comprising longitudinally parallel elastic and non-elastic sections each of substantial width, and an edge cord, said elastic section being woven with elastic wefts only and said non-elastic section being woven with non-elastic wefts only, the elastic section being woven two-up and two-down in a rib weave 40 and the non-elastic section being woven two-up and two-down in a twill weave in the portion adjacent the elastic section and being woven tubular about the inserted edge cord in its outer edge portion, and each pair of adjacent picks of elastic weft in the elastic section being connected by a terminal loop enclosing within itself a terminal loop connecting a pair of non-elastic weft picks whereby the elastic wefts and the non-elastic wefts are interlocked and the elastic and non-elastic sections permanently joined at their abutting margins.

JOHN V. MOORE.
